UNITED STATES PATENT OFFICE.

MARTHA J. HERBSTERET, OF URBANA, ILLINOIS.

COLANDER.

1,139,033.

Specification of Letters Patent. Patented May 11, 1915.

Application filed February 10, 1914. Serial No. 817,903.

To all whom it may concern:

Be it known that I, MARTHA J. HERBSTERET, a citizen of the United States, residing at Urbana, in the county of Champaign and State of Illinois, have invented certain new and useful Improvements in Colanders, of which the following is a specification.

My invention relates to an improved colander or strainer.

The invention aims to provide a generally improved construction of device of this kind and one that is especially improved with respect to means to positively compress the contents being strained or drained, means to support an inner or contents containing vessel within the main vessel, means to fasten the vessel against independent rotary movement and to provide the compressing means in the nature of a weight or plate movable vertically within the inner vessel upon actuation of a screw rod.

With the above and other objects in view, the invention has been embodied in one form in the device described hereinafter in connection with accompanying drawings wherein:

Figure 1 is a vertical sectional view of the colander. Fig. 2 is a cross-section on the line 2—2 of Fig. 1. Fig. 3 is a top view of the colander. Fig. 4 is a view similar to Fig. 3 with the operating crank cross bar and fastening pins for the cross bar removed. Fig. 5 is a cross section on the line 5—5 of Fig. 1 and Fig. 6 is a detail perspective view showing one fastening means for the bar, the colander and bar fragmentarily, all associated.

Referring specifically to the drawings and wherein like reference characters designate like or corresponding parts an outer or main cylindrical vessel is provided comprising a lower liquid receiving chamber 1 and an inner vessel containing chamber 2 of greater diameter than that of the chamber 1 and having its wall integral with that of said chamber 1. The chambers providing at their junction a ledge or shoulder 3. A bottom wall 4 is provided on chamber 1 and depending therefrom are supporting legs 5 which rest on a suitable support as at 8. Any suitable means may be provided to rigidly clamp the main vessel to a support. Such a clamp means is shown and as its particular construction forms no part of the present invention it will be merely generally

referred to as shown at 12 attached to support 8.

Within the upper or large chamber 2 is a removable cylindrical container vessel 13 having an inwardly extending flange 14 which directly rests on the ledge or shoulder 3 and supports the vessel 13. A perforated bottom plate or wall 15 for the container is supported on flange 14. Preferably a plurality of vessels 13 are employed with a single device but for use one at a time, the perforations of the bottom plates of the different vessels differing in sizes so that the article may be used with substances of different constitution or consistency.

A screw rod 16 is rotatably mounted within the vessel 13, at its lower end in the plate 15 by a nut 16' and at its upper end rotatably mounted in a bar 17 which will later be described. Beyond the bar 17, the rod 16 has a square or otherwise polygonal shank 17' which extends through an opening of a crank handle 18 and is provided with a screw threaded stud 19 beyond the handle 18 receiving a fastening nut 20.

Within the inner vessel 13 is a vertically movable, heavy compressor plate 21. This plate has screw threads at a center opening 22 to engage the screw threads of the rod 16, which rod passes through said opening. Said plate is mounted against turning movement relatively to the rod 16 and to this end may have one or more lugs 23 to slide in grooves 24 provided longitudinally and inferiorly of the vessel 13.

Bar 17 in addition to serving as a bearing for the rod 16 serves to fasten the two vessels 1 and 13 against independent rotary movement. The outer or main vessel has integral therewith on opposite sides spaced apart lugs 25 which extend upwardly from the upper edge and the inner vessel has integral lugs 26 which extend upwardly from the upper edge and align with the lugs 25. Bar 17 removably rests between the lugs 25 and 26 and may be locked against vertical displacement by pins 27 extending above and across the same and through eyes in the lugs 25 as shown.

One or more blades 28 may be provided on the rod 17 over and adjacent the bottom plate 15 to function as a stirrer and somewhat as a scraper.

In use the parts are fastened as in Fig. 1 with receptacle 13 within the outer receptacle resting on ledge 3 and fastened against

rotary movement independently of the outer receptacle by the fastened bar 17. Handle 18 is then turned to turn the screw 15, which causes descent or downward sliding movement of the compressor weight or plate 21 against the contents of container or vessel 13, causing the liquid to emerge from the solid matter through the perforations of plate 15, the blades 28 serving to 10 prevent packing or clogging of the contents of vessel 13 at the plate 15. Said liquid accumulates in the chamber 1. All parts are removable and detachable to facilitate cleaning.

15 Reserving all changes within the spirit and scope of the invention, I claim:

1. A colander having a main vessel provided with an upper and a lower chamber with a ledge at their junction, a removable vessel in the upper chamber resting on said ledge, outlet means from said second chamber, a plate in said second vessel mounted against turning movement relatively to the second vessel, a bar, projections on said vessels engaged by said bar to prevent independent turning movement of the vessels,

a removable screw rod passing through said plate, screw threads on the plate engaging the rod passing through said plate, screw threads on the plate engaging the rod, said rod also extending through said bar as a bearing and to prevent displacement thereof and the bottom of said second vessel as a bearing, and an operating member on said rod.

2. A colander having a main vessel, a removable vessel mounted therein, abutment means on each of said vessels, a plate movable longitudinally of the removable vessel, a turnable rod passing through said plate, means to move the plate through movement of said rod, a bar removably disposed between said abutment means to prevent relative turning movement of the vessel, and said rod and bar engaging to prevent displacement of the bar radially of the vessels.

In testimony whereof I affix my signature in presence of two witnesses.

MARTHA J. HERBSTRIET.
